CLAIM

The ornamental design for a light emitting diode (LED) package, as shown and described herein.

DESCRIPTION

FIG. 1 is a perspective view of a light emitting diode (LED) package in accordance with an embodiment of the present invention.

FIG. 2 is a front view of the LED package.

FIG. 3 is a rear view of the LED package.

FIG. 4 is a left side view of the LED package.

FIG. 5 is a right side view of the LED package.

FIG. 6 is a top view of the LED package.

FIG. 7 is a bottom view of the LED package; and,

FIG. 8 is a cross-sectional view taken along line 8-8 in FIG. 6.
